Primary Examiner — Selina Sikder*(74) Attorney, Agent, or Firm* — Banner & Witcoff, Ltd.(57) **CLAIM**

The ornamental design for a somatosensory controller, as shown and described.

DESCRIPTION

FIG. 1 is a front perspective view of a somatosensory controller showing my new design;

FIG. 2 is a rear perspective view thereof;

FIG. 3 is a top view thereof;

FIG. 4 is a bottom view thereof;

FIG. 5 is a front view thereof;

FIG. 6 is a rear view thereof;

FIG. 7 is a side view thereof;

FIG. 8 is another side view thereof;

FIG. 9 is a front perspective view of a somatosensory controller showing an alternative embodiment of my new design;

FIG. 10 is a rear perspective view thereof;

FIG. 11 is a top view thereof;

FIG. 12 is a bottom view thereof;

FIG. 13 is a front view thereof;

FIG. 14 is a rear view thereof;

FIG. 15 is a side view thereof; and,

FIG. 16 is another side view thereof.

The broken lines shown in the FIGS. 1-8 represent unclaimed subject matter and form no part of the claimed design.

1 Claim, 10 Drawing Sheets(56)
